UNITED STATES PATENT OFFICE.

DAVID H. COUCH, OF WARWICK, RHODE ISLAND.

SUSPENDED IGNITION ARCH.

Application filed December 14, 1922. Serial No. 606,900.

This invention relates especially to arches over extended furnaces generally known as "Dutch ovens". Such arches are usually called "ignition" or "combustion" arches and function as heat reflectors which improve combustion by creating a hotter zone near where the fuel is being burned. This causes a more rapid and complete combustion than would be the case if the fire were directly exposed to the cold boiler surfaces which absorb so much heat by radiation that the furnace is robbed of its heat so rapidly that it cannot generate heat fast enough to keep the fuel properly ignited until combustion is completed. In other words such an arch is provided to help form a hot refractory furnace to assist in the complete combustion of the fuel being used.

The principal objects of my invention are as follows: First, to provide a type of suspended ignition or combustion arch which will have a sufficient amount of refractory material to give the necessary aid to combustion of the fuel being used; second, to provide a type of suspended ignition arch which will be durable and dependable and one which will not have to be immediately taken out of service if parts of the refractory material fall out, as is the case with suspended arches now on the market; third, to provide an arch which will act, not only as a refractory heat reflector, but one which, in the case of steam boilers, will add greatly to the steam making capacity of the boiler by providing additional heating surface so arranged as to absorb a very large amount of heat from the furnace, much of which heat is usually wasted thru the present types of suspended ignition arches.

40 Other objects will appear in the specifications and claims appended thereto.

These objects are attained in the case of furnaces for steam boilers by making the supporting members of the arch of steel or metallic tubes, the lower ends of which are expanded into or otherwise securely attached to a header. This header communicates by means of one or more pipe connections to the water space of the boiler. The upper ends of said tube supporting members communicate with the boiler steam or water drums or headers, below the water line, but at a higher elevation than the connection just described at the lower ends of these tubes. This makes it possible for some of the boiler water to circulate thru these tubes

and prevent them from becoming overheated. Around these supporting tubes refractory tile, preferably taking the form of a C and usually known as C tile, is placed to form the refractory portion of the arch. Above the zone which it is desired to keep highly heated, tile taking the form of a T and generally known as T tile may be used on the outside only of the supporting tubes. This allows the tubes to absorb more heat from the furnace by convection or in some cases both by convection and by radiation than would be possible if C tile only were used. Other forms of tile answering the same purpose may be used or the refractory material may be applied in a plastic form and allowed to harden, the essence of the invention being the use of tubes or hollow members thru which water, or in certain cases, other liquid circulates by convection or is circulated by a pump or other means as the supporting members of the arch and refractory material surrounding or resting on said supporting members to form the necessary refractory portion of the arch.

The type of boiler to which this arch is to be applied will determine whether a top header will be required to receive the top ends of the supporting tubes or whether these tubes may be attached directly to or expanded into the steam drums, headers or other heating surface of the boiler. In the case of Sterling type boilers, the top ends of the tubes may be expanded directly into the front steam drum, while in the case of the Bigelow-Hornsby type boiler a top header with connections at intervals to the drums will be necessary.

The accompanying drawing shows the application of this invention to a Sterling boiler, but many other types of boilers may be equipped with this arch with slightly different details in the means of top and bottom connections to the boiler. Also in some cases it may be found that natural convection currents in the circulating liquid are not sufficient to give the necessary circulation, in which cases a pump or equivalent device may be used in series with the arch to produce the required circulation. This arch may be used with stills or other liquid heating vessels with practically the same type of connections as that described and illustrated in the case of steam boilers but in cases where the pressure of the circulating liquid is low, hollow castings or other

forms of hollow arch supporting members may be used instead of tubes.

This arch may also be used with some types of industrial furnaces, not used in connection with liquid heating vessels, in which cases water or other suitable liquid may be pumped through or caused by other means to flow thru the arch supporting members and this water or other liquid, may 10 be used, for industrial purposes, cooled and re-circulated or disposed of as desired.

The preferred embodiment of my invention is shown on the accompanying drawing in which Fig. 1 shows a vertical transverse 15 section of a Sterling boiler showing the application of my invention to this type of boiler; Fig. 2 shows a partial plan view of Fig. 1 taken along the line 1—1, Fig. 3 is a detail view of a cross section of the 20 header at the lower ends of the tubes showing the cast iron protection and tile support for the bottom of the headers, Fig. 4 is a transverse section at the line 4—4 of a few 25 of the supporting tubes 2, T tile 5, and T irons 40, and Fig. 5 is a transverse section at the line 5—5 of some of the supporting tubes 2, C tile 4 and insulating covering 48.

Similar numerals refer to similar parts throughout the several views.

30 Referring to the Figures, 2 represents the supporting tubes of the arch, 3 is the connecting header at the lower ends of the tubes 2 into which these tubes are expanded or otherwise suitably attached, 4 is the C 35 tile or refractory portion preferably entirely surrounding the tubes where the hottest zone is required. 5 is preferably a T tile upper refractory portion where a high temperature is not required and it is not necessary therefore to entirely surround the 40 tubes with refractory tile, 6 is the connecting pipe permitting the circulation of water from the mud drum 9 thru the header 3 and tubes 2 to the front steam drum 10. 45 Pipe 6 is connected to the header 3 and mud drum 9 by the T's 7 and 8, each of which has one end blanked by a removable flange to facilitate cleaning. 11 is a blow down 50 valve at the end of header 3 to permit of blowing the water and sediment out of header 3 and tubes 2. Valve 11 is connected to the header 3 by the flanges 12 and 14 and the nipple 13. 15 is a tube or tubes connected between the top of header 3 and steam drum 10 in order to readily convey 55 to drum 10 any steam which might be generated in the header 3 and become trapped above the inlets to tubes 2.

60 The boiler consists of the mud drum 9, the steam drums 10, 16 and 17 and the tube banks 18, 19, 20, 21, 22 and 23 housed and protected by the setting walls 24, 25 and 26 which rest on the floor 27. The fuel is burned on the stoker or grate or in the burner or other apparatus 28 and the prod-

ucts of combustion pass up and down among the tube banks 18, 21, 19 and 20 being directed in their course by the baffles 29, 30, 31 and 32 and are finally discharged past the damper 33 and thru the outlet 34 to the 70 breaching not shown.

The arch is supported at the upper end by the tubes 2 being expanded into or otherwise suitably connected to the steam drum 10. The header 3 is hung from the I beam 75 or other support 35 by the hangers 36. These hangers 36 are preferably attached to the header 3 by lugs, not shown, riveted or welded onto the header 3 or attached by other suitable means. 80

The C tile 4 surround and are supported by the tubes 2, while the T tile 5 rest on the brackets 37 which are attached to the steel channel 38 by the bolts 39. Brackets 37 therefore support the weight of the T 85 tile 5, but these tile 5 are held in position against the tubes 2 by the angle irons or T irons 40 which are held in place at the lower end by a projection which rests against the inside top surface of the channel 38 and are held in place at the top end by hook bolts 41 which hook around the tubes 2. There is one of these angle or T irons 40 and brackets 37 for each column of T tile between each two adjacent tubes. The 90 top of the C tile portion 4 of the arch is preferably protected from further loss of heat by the insulating covering 48 and this construction may also be employed on the outside of the T tile 5 if desired. 95

Header 3 is protected from the heat of the furnace by a cast iron protecting sheath 42 held in place by the straps 43, Fig. 3. The lower side of these protecting pieces 42 has a T projection onto which are slipped 105 refractory protecting tile 44, the object of which is to further protect the header 3 and the joint between the C tile 4 and the cast iron protecting pieces 42. Access for expanding, cleaning or removing tubes 2 110 is provided by a handhole opposite each tube 2. These handholes are closed by handhole plates 45 which are held in place by the saddle or cap 46 and the nut 47.

It is understood that the invention is not 115 limited to the specific embodiment shown and that various deviations may be made therefrom without departing from the spirit and scope of the appended claims.

What I claim as new and desire to secure 120 by Letters Patent is:

1. A steam boiler having a bank of vertically extending water tubes, upper and lower drums connected to the ends of said water tubes, a furnace chamber in front of and beneath said bank of tubes, a baffle to direct the gases from said furnace along said water tubes to the upper ends thereof adjacent said upper drum, a row of combustion arch tubes extending substantially 125 130 135

horizontally over the lower part of said furnace and then substantially upwardly, the tubes of said row being connected at their upper ends to said upper drum and at 5 their lower ends to a header, connections between said header and said lower drum, tile surrounding the substantially horizontal portions of said arch tubes and arranged to close the spaces therebetween, and tile covering the spaces between the substantially vertical portions of said arch tubes to form 10 a front furnace wall and arranged to expose said substantially vertical portions to the gases rising along said bank of water tubes.

15 2. A steam boiler having a bank of vertically extending water tubes, upper and lower drums connected to the ends of said water tubes, a furnace chamber in front of and beneath said bank of tubes, a baffle to direct the gases from said furnace along 20 said water tubes to the upper ends thereof adjacent said upper drum, a row of combustion arch tubes extending substantially horizontally over the lower part of said furnace and then substantially upwardly, 25 the tubes of said row being connected at their upper ends to said upper drum and at their lower ends to a header, connections between said header and said lower drum, tile surrounding the substantially horizontal portions of said arch tubes and arranged to close the spaces therebetween, and tile covering the spaces between the substantially vertical portions of said arch tubes to form 30 a front furnace wall and arranged to expose said substantially vertical portions to the gases rising along said bank of water tubes, said substantially vertical portions having an angle to said bank of water tubes to form an upwardly progressively 35 contracting combustion space.

In testimony whereof I have affixed my signature.

DAVID H. COUCH.
